FLYING MACHINE

Richard J. McNamara, Somerville, Mass., assignor of one-half to Edward J. Blanchfield, Cambridge, Mass.

Application February 14, 1936, Serial No. 63,887

9 Claims. (Cl. 244—17)

This invention relates to flying machines and more particularly to improving the wings for a flying machine.

One object of my invention is to provide new wings for flying machines such as the helicopter type, which meet the air without an initial impact shock and which will accelerate the air downwardly at an increasing speed and angle as it traverses the wings, while said wings rotate at a comparatively low speed, thereby attaining great lifting efficiency.

Another object is to provide such a construction and arrangement of wings that increasing the diameter of the wings, while maintaining the same tip speed, substantially increases the lift per horse power, and the lift per unit area, thereby increasing the efficiency of the flying machine as it is increased in size.

The foregoing and other objects which will appear as the nature of the invention is better understood, may be accomplished by a construction, combination and operative arrangement of parts such as is disclosed by the drawing and specification. The nature of the invention is such as to render it susceptible to various changes and modifications, and, therefore, I am not to be limited to said disclosure; but am entitled to all such changes therefrom as fall within the scope of my claims.

30 In the drawing:

Figure 1 is a perspective view of a flying machine equipped with my wings.

Figure 2 is a front elevation view of my wings in operable position on a flying machine.

35 Figure 3 is a side elevation view of my wings as shown in Figure 2.

Figure 4 is a plan view of my wings as shown in Figure 2.

Figure 5 is a sectional view taken on the line 40 5—5 of Figure 4, showing the curvature or camber of a wing as it appears when stationary.

As illustrated, a flying machine 7 is equipped with two of my wings 8 which are fixed to a bracket 9 fixed to a sleeve 11, which in turn is fixed to a rotatable shaft 15, mounted to and rotatable by a motor 16 of well known type. Thus it will be seen that fastening said shaft 15 to said wings 8 results in the rotation of said shaft and wings together.

50 Each wing 8 is flat, and is so shaped and positioned as to constitute, while being rotated, a quadrant of the disk area swept by the said wings 8, as illustrated in Figures 3 and 4 of the drawing. The front or leading edges 18 of said wings 55 8 extend outwardly and upwardly from opposite

sides of said shaft 15 at an angle of 45 degrees, and said leading edges of the two wings extend in opposite directions and are in alinement with each other, as shown in Figure 4 of the drawing. This angle may be varied somewhat, but any variation of more than five degrees either way results in a noticeable decrease in efficiency. The trailing or rear edges 19 of said wings 8 extend horizontally from opposite sides of said shaft 15 and are in alinement with each other as shown in Figure 4 of the drawing. The said leading edge 18 of a wing forms an angle of 90 degrees with said trailing edge 19, and its actual physical length is substantially greater than said trailing edge 19, as will be seen in Figures 2 and 3 of the drawing. The tip or curved edge 20 of said wings 8 defines the circumference of the disk area swept by my wings 8 when rotating.

As shown in Figure 4 of the drawing, in a plan view the distance, measured horizontally outward along a said trailing edge 19 from the center of said shaft 15 to any point on said tip edge 20 of my wings is always the same, consequently my said wings sweep the air in a circle when rotated.

My wings may be made of the usual wing material; such as air craft steel covered by treated fabric. The under side of said wings is given the numeral 21 and the upper side 22. As the wings 8 are rotated the air strikes said under side 21 and upper side 22 at a very slight angle, and thereby avoids any initial impact shock, and it then passes down on both said under and upper sides 21 and 22 at an ever increasing angle and velocity due to the rotation of the wings 8, which rotation continuously presents more wing surface 30 of said under side 21 in contact with the air until it passes beyond the wings at the said trailing edges 19, as indicated by the arrows in Figure 4 of the drawing. The rotation of said wings 8 increases the camber of the wing surface which 40 the air follows, with the result that the velocity of the air is continuously increased until it passes beyond the wings. This camber is substantially greater while the wings are being rotated than the stationary camber shown in Figure 5 of the drawing. From this it will readily be seen that the larger the wings 8 and therefore the greater the diameter of the disk area swept by the said wings, the greater the lifting efficiency of the flying machine so equipped.

55 What I claim is:

1. A wing rotor device for a flying machine comprising a shaft extending upwardly, means to rotate said shaft, and two wings only fastened to said shaft the leading edges of which extend 55

- diagonally outward and upward from said shaft in substantially opposite directions and are at right angles to the trailing edges which extend substantially horizontally in opposite directions 5 from said shaft.
5. A wing rotor device for a flying machine comprising a shaft extending upwardly, means to rotate said shaft, and two wings fastened to said shaft and extending outwardly therefrom 10 in different directions, each said wing embodying a leading edge and a trailing edge which is shorter in physical length than said leading edge, and a curved tip outside edge extending between said leading and trailing edges, said leading edges extending outwardly from said shaft at such an angle that the distance from said shaft horizontally outward to any point in vertical alinement with said tip edges is substantially the same as the said physical length of said trailing 15 edge.
10. A wing rotor device for a flying machine comprising a shaft extending upwardly, means to rotate said shaft, and two wings only fastened to said shaft each embodying a leading edge, a 15 trailing edge and a curved tip outside edge extending between said other two edges, said trailing edge being physically shorter than said leading edge, said two leading edges extending diagonally outward and upward from said shaft in substantially opposite directions in substantial alinement with each other, said two trailing edges extending substantially horizontally outward from said shaft in substantially opposite directions in alinement with each other and at substantially 20 an angle of ninety degrees to said leading edges.
15. A wing rotor device for a flying machine comprising a shaft extending upwardly, means to rotate said shaft, and two wings fastened to said shaft and extending outwardly therefrom in different directions, each said wing embodying a leading edge and a trailing edge which is shorter in physical length than said leading edge, and a curved tip outside edge extending between said leading and trailing edges, each said leading edge extending diagonally upward from said trailing edge at said shaft at an angle between 40 and 50 degrees to a plane perpendicular to said shaft, each said trailing edge extending substantially 25 horizontally outward from said shaft in different directions, said wings being of such shape and so positioned with relation to each other that each said wing forms substantially a quadrant of the circle swept by the tip edges of said wings.
20. A wing rotor device for a flying machine comprising a shaft extending upwardly, means to rotate said shaft, and wings fastened to said shaft and extending outwardly therefrom in different directions, the surfaces of said wings 30 being entirely flat, each said wing embodying a leading edge, a trailing edge, and a curved tip outside edge extending between said leading and trailing edges, each said trailing edge extending substantially horizontally outward from said shaft, each said leading edge extending diagonally upward from said trailing edge, each said tip edge being of such curvature that the distance from said shaft horizontally outward to any point in vertical alinement with said tip edge is substantially the same as the physical length of said trailing edge. 5
25. A wing rotor device for a flying machine comprising a shaft extending upwardly, means to rotate said shaft, and two wings only fastened to said shaft the leading edges of which extend diagonally outward and upward from said shaft in different directions and into different quadrants of the circle swept by said wings and are at substantially right angles to the trailing edges 10 which extend horizontally from said shaft in different directions and into different quadrants of said circle. 15
30. A wing rotor device for a flying machine comprising a shaft extending upwardly, means to rotate said shaft, and two wings only fastened to said shaft the leading edges of which extend diagonally outward and upward from said shaft in different directions and into different quadrants of the circle swept by said wings and are 20 substantially perpendicular to the trailing edges which extend outwardly from said shaft in different directions and into different quadrants of said circle. 25
35. A wing rotor device for a flying machine comprising a shaft extending upwardly, means to rotate said shaft, and two wings fastened to said shaft the leading edges of which extend diagonally outward and upward from said shaft in different directions at an angle of between 40 and 50 degrees to a plane substantially perpendicular to said shaft, and the trailing edges of which extend outwardly in a lesser angular direction than said leading edges' angle, each said wing being of such shape and so positioned as to form substantially a quadrant of a circle swept by said wings. 30
40. A wing rotor device for a flying machine comprising a shaft extending upwardly, means to rotate said shaft, and two wings fastened to said shaft the leading edges of which extend diagonally outward and upward from said shaft in opposite directions at an angle of between 40 and 50 degrees to a plane substantially perpendicular to said shaft and are at right angles 45 to the trailing edges which extend substantially horizontally from said shaft in opposite directions. 50
45. A wing rotor device for a flying machine comprising a shaft extending upwardly, means to rotate said shaft, and two wings fastened to said shaft the leading edges of which extend diagonally outward and upward from said shaft in opposite directions at an angle of between 40 and 50 degrees to a plane substantially perpendicular to said shaft and are at right angles 55 to the trailing edges which extend substantially horizontally from said shaft in opposite directions. 55
